UNITED STATES PATENT OFFICE.

WEBSTER L. MARBLE, OF GLADSTONE, MICHIGAN.

DESIGN FOR A BLADE FOR A HUNTING-KNIFE.

48,624.

Specification for Design.

Patented Feb. 22, 1916.

Application filed May 22, 1915. Serial No. 29,924. Term of patent 14 years.

To all whom it may concern:

Be it known that I, WEBSTER L. MARBLE, citizen of the United States, residing at Gladstone, in the county of Delta and State of Michigan, have invented a new, original, and ornamental Design for a Blade of a Hunting-Knife, of which the following is a specification, reference being had to the accompanying drawing, forming part thereof.

Figure 1 is a side elevation of the blade of a hunting knife embodying my new de-

sign; a handle being conventionally represented by dotted lines. Fig. 2 is a top plan view of the blade and a portion of the shank.

I claim:

The ornamental design for the blade of a hunting knife, as shown.

In testimony whereof I affix my signature.

WEBSTER L. MARBLE.
